UNITED STATES PATENT OFFICE.

FRANK E. ANDERSON, OF ST. JAMES, MINNESOTA.

WAGON-RACK BRACKET.

1,267,162.

Specification of Letters Patent. Patented May 21, 1918.

Application filed February 9, 1916. Serial No. 77,244.

To all whom it may concern:

Be it known that I, FRANK E. ANDERSON, a citizen of the United States, residing at St. James, in the county of Watonwan and State of Minnesota, have invented new and useful Improvements in Wagon-Rack Brackets, of which the following is a specification.

This invention relates to a bracket which may be applied to the sills on wagon racks and when connected therewith will engage with the rear bolsters on the running gear of a wagon and prevent longitudinal movement of the wagon rack upon the bolsters.

15 The primary object of the invention is to provide a bracket of the class described which not only prevents longitudinal movement of the wagon rack upon the bolster, but also prevents chafing of the wagon bolsters and rack and enables the front portion of the rack to be raised and lowered when the bolster is gripped between clamping jaws on the bracket.

Another object of the invention is to provide brackets for the purpose described which may be attached to sills of wagon racks which have become chafed and worn away by contact with the wagon bolsters and when applied to the sills will materially strengthen the same and permit the wagon rack to be used longer under these conditions than would otherwise be possible with brackets for this purpose now in use.

Another object of the invention is to provide the brackets with oppositely diverging clamping jaws having curved portions at their lower edges so arranged that when the brackets are applied to the sills of a wagon rack and the rack positioned upon the front bolster of the wagon the curved portions on the jaws will assist in positioning the rear bolster on the wagon between the clamping jaws on the bracket when the wagon rack is dropped.

45 A still further object of the invention is to provide the diverging clamping jaws on the bracket with rounded side edges, so that when the sills of the wagon rack converge toward the forward bolster on the running gear to permit the wagon to be turned in a narrow space, the side edges of the jaws will not chafe or mar the rear bolster, said jaws also permitting the use upon the rear

bolster of an auxiliary bolster when the rear bolster has become weakened and mutilated through long continued use.

A still further object of the invention is to provide webs upon opposite sides of the clamping jaws which serve to strengthen the same and enable the jaws to be made of thinner material than would otherwise be possible, thus decreasing the cost of manufacture of the brackets.

With these and other objects in view the invention resides in the novel combination and arrangement of parts which will be hereinafter described and particularly pointed out in the claim.

The preferred embodiment of the invention has been illustrated in the accompanying drawing, although no restriction is necessarily made to the precise details of construction therein shown, as changes, alterations and modifications within the scope of the appended claim may be resorted to when desired.

In the drawing,

Figure 1 is a side elevation of the rear portion of the running gear of a wagon showing a portion thereof broken away to more clearly illustrate the manner of connecting a wagon rack with the rear bolster by means of the improved bracket.

Fig. 2 is a vertical transverse sectional view taken centrally through the bracket and showing the same connected with one sill of a wagon rack.

Fig. 3 is a detail perspective view of the bracket showing the same detached from the sill of the wagon rack.

Fig. 4 is a vertical longitudinal sectional view on the line 4—4 of Fig. 2.

Fig. 5 is a horizontal transverse sectional view on the line 5—5 of Fig. 1.

Like characters of reference denote corresponding parts throughout the several views.

Referring now to the drawing in detail, the numeral 1 designates the rear portion of the running gear of a wagon having the usual rear bolster 2 upon which is mounted a wagon rack 3 including sills 4, said rack being held from longitudinal movement thereon by means of the improved bracket designated by the numeral 5.

This bracket comprises a rectangular base

8 provided on its under face with oppositely inclined surfaces 9 at each end, between which are disposed a thickened intermediate portion 10. Each reduced portion of the base 8 is provided with spaced vertically extending openings 11 through which may be passed suitable fastening elements 12, such as lag screws or the like, for engagement with the sills 4.

- 10 Depending from the underside of the base 8 at the point of intersection of the oppositely inclined portions 9 with the thickened portion 10 are spaced and oppositely inclined clamping jaws 13, the lower edges, 15 14, of which are curved outwardly toward the ends of the base 8. The side edges of the clamping jaws 13 are also rounded, as indicated by the numeral 15, so that when the brackets are used upon wagon racks 20 where the sills 4 converge toward the forward bolster, the rear bolster is prevented by the rounded edges 15 from becoming chafed through their contact with the bolster.

- 25 Webs 16 are arranged at each end and upon opposite sides of the base 8 and are formed integral with the oppositely inclined portions on the base and with the side edges of the jaws 13, said webs serving to reinforce the base and the clamping jaws 13, and being provided with an inwardly curved side edge 17.

- Extending upwardly from one side of the base 8 at opposite ends are attaching ears 35 18, each of which is provided with an opening 19 adapted to have passed therethrough fastening elements 20 which in this instance have been shown as bolts, by means of which the ears and brackets may be secured 40 to the sills 4. When the brackets have been secured to the under faces of the sills 4 of the wagon rack by means of the bolts 20 and screws 12, the rack may be positioned upon the running gear of the wagon in the following manner: The front of the wagon 45 rack is disposed upon the front bolster of the wagon and the rack pushed forwardly and held above the rear bolster until the clamping jaws 13 are above the rear bolster. The rear end of the wagon rack is now lowered, and the curved bottom edges 50 14 of the clamping jaws 13 serve to guide the rear bolster into contact with the thickened portion 10 of the plate 8.

- 55 When the forward ends of the sills 4 of the wagon rack converge toward the front bolster to permit the wagon to be turned in a limited space, it will be noted that the curved side edges 15 of the clamping jaws 60 prevent the rear bolster being chafed by the jaws on the brackets, and that in providing the brackets with the oppositely inclined clamping jaws the front of the rack may be raised or lowered, as desired, this being con-

sidered an important feature of this invention. 65

The jaws 13 are sufficiently long and tapered in such a manner that an auxiliary bolster may be positioned upon the rear bolster of the running gear when said bolster 70 has become mutilated or worn through long and continuous use, both bolsters being gripped by the oppositely diverging clamping jaws, while the thickened portion of the base materially strengthens the bracket 75 should the sills of the wagon rack have become worn through their contact with the bolster.

With reference to Fig. 4 of the drawing, it will be seen that the oppositely inclined 80 portions 9 of the base 8 enable the fastening elements 12 to be inserted in the sills 4 at an angle so that the screws are prevented from becoming loose through the strain imposed upon the brackets by the sills, and also that 85 through the use of screws at this point water is prevented from entering the holes for the fastening elements and causing the sills to decay.

From the foregoing description taken in 90 connection with the accompanying drawing, it will be apparent that a wagon rack bracket has been provided which when connected with the rack and engaged with the bolsters on the running gear of a wagon 95 will prevent longitudinal movement of the rack upon the bolsters and prevent the same from becoming worn or mutilated and also enable various adjustments of the rack with relation to the forward bolster to be made. 100

Having thus described the invention, what is claimed as new is:—

A bracket for the purpose set forth, comprising a casting shaped to provide a flat substantially rectangular base, the central portion thereof being of an equal thickness throughout and the under face of which is beveled or gradually decreased in thickness from the said central portion to the ends of the said base, the base, upon its upper face, and at one of its sides having outstanding ears, the inner faces of which are arranged at a right angle to the flat outer surface of the base, and each of said ears having a central transverse opening, the inclined ends 110 of the base having spaced openings struck at a right angle with respect to the said inclined surfaces and designed to receive securing elements whereby the said securing elements will be arranged at an inward angle with respect to the bracket and be disposed in pairs to the opposite sides of the opening in the respective ears, whereby a securing element passing through the openings in the said ears will be disposed centrally between the said securing elements passing through the openings in the base, said base, at its juncture with the referred 115 120 125

to inclined ends having depending members, the outer corner faces of which are straight or at a right angle with respect to the central portion of the base, and the inner portions of which are beveled or gradually increasing in thickness from the ends thereof to their juncture with the base, and web members integral with the referred to depending members and the beveled ends of

the base and arranged upon the opposite 10 sides of the bracket.

In testimony whereof I affix my signature in presence of two witnesses.

FRANK E. ANDERSON.
